UNITED STATES PATENT OFFICE

126,408

DESIGN FOR SCISSORS

Martin E. Trolle, St. Paul, Minn., assignor to Brown & Bigelow, St. Paul, Minn., a corporation of Minnesota

Application April 25, 1940, Serial No. 91,946

Term of patent 14 years

To all whom it may concern:

Be it known that I, Martin E. Trolle, a citizen of the United States, residing at St. Paul, county of Ramsey and State of Minnesota, have invented a new, original, and ornamental Design for Scissors, of which the following is a specification, reference being had to the accompanying drawing, forming part thereof.

showing my new design.

ure 1.

ure 1.

I claim:

The ornamental design for scissors, as shown.

MARTIN E. TROLLEN.
